MEDICAL DEVICE

Ruth W. Munro, Winchester, Mass.

Application November 15, 1932, Serial No. 642,799

2 Claims. (Cl. 128—271)

This invention relates to improvements in medical devices and pertains particularly to a soluble pessary.

The primary object of the present invention is to provide a pessary which is formed of any suitable substance which will be completely dissolved by the heat of the body when the pessary has been placed in position in the body cavity which it is designed to medicate, and which is chambered and has such chamber or chambers filled with a medicinal substance which will be slowly liberated as the device dissolves.

A further object of the invention is to provide a pessary which may be formed in any one of a number of different shapes, in which the medicament is contained in a number of chambers therein whereby an even distribution thereof will be obtained as the device dissolves.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 is a view in transverse section through one form of the device embodying the present invention, the device being of circular design and the section being taken on a plane extending parallel to the axis thereof;

Figure 2 is a sectional view through a modified form of the device;

Figure 3 is a horizontal sectional view taken upon the line 3—3 of Figure 2;

Figure 4 is a longitudinal sectional view through a further modification of the device;

Figure 5 is a view illustrating a cross section of a pessary of the general character of that shown in Figure 4 but with the elongated portion longitudinally fluted to permit of more ready compression and reduction of the circumference.

Referring now more particularly to the drawing wherein like numerals of reference indicate corresponding parts throughout the several views, the numeral 1 indicates generally one of a number of forms in which a pessary may be formed and embody the present invention.

In this form the body of the pessary is made of circular outline and its peripheral surface is curved transversely as indicated at 2 while the

opposite faces thereof have formed therein the depressions or cavities 3 for the purpose herein-after described. The body of this device may be formed of any suitable substance which will slowly dissolve at body heat when the device is placed in the body cavity which it is designed to medicate. It is preferable that the substance be so compounded as to melt away or dissolve extremely slowly so that the medicating substance contained therein will be discharged at a slow rate and thereby prolong its medicating effect upon the surrounding surfaces. It is, of course, understood that the substance of which the body is formed must be of a character which may be absorbed with the medicament and which will not introduce any matter into the body cavity which would have a harmful effect upon the membranous lining thereof.

As shown, the body 1 is made hollow thus forming the chamber 4 and this chamber, which in the present form of the device covers the entire interior area of the body, has introduced therein the medicating substance 5 which may be in the form of a liquid or a salve. This substance may be of an antiseptic nature entirely or it may contain demulcent substances or narcotic drugs where the use of such treatment is indicated.

Figure 2 shows a modification of the form of the device illustrated in Figure 1.

This form is indicated generally by the numeral 6 and like the device 1 is of circular contour and has the circumferential surface transversely arcuate or rounded as indicated at 7 and the opposed cup-like depressions or pockets 8 in the side faces. This form, however, has a central area 9 which separates the medicine containing chambers and these chambers are preferably as shown in Figure 3 where each is indicated by the numeral 10. In this construction the body has formed therein at each side of the central solid area the two circular groups of small chambers in each of which the medicating substance which is here indicated by the numeral 11, may be placed. It will, of course, be understood that if desired the group of chambers 10 at each side of the central area 9 may be merged so that the entire body will contain only two chambers which will be divided by the central solid portion.

If desired, the central portion 9 of the form of the device illustrated in Figures 2 and 3 may be formed of a substance which dissolves at body heat even more slowly than the portion of the body which outlines the pockets or cavities 8 so

that the walls of these cavities and the adjacent portions of the curved circumferential wall 7 may melt away before the central area 9 melts.

Figure 4 illustrates still another form of the invention wherein the fundamental idea is embodied. In this form there is provided a circular head portion which is indicated as a whole by the numeral 12 and which has the cylindrical portion 13 extending from one side thereof.

10 This portion 13 is hollow, opening through its outer end as shown, while its inner end is rounded out as indicated at 14. Opposite the rounded hollow inner end 14 of the cylindrical portion 13 the body has the cup-like cavity 15 therein and between these cavities 14 and 15 is formed the chamber 16 in which the medicating substance 17 is placed. This chamber 17 may be a continuous circular chamber like the chamber 5 in the form of the device illustrated in Figure 1 or it may be divided by radial walls so as to form a plurality of small chambers as illustrated in Figure 3 in connection with the device indicated by the numeral 6.

Figure 5 represents a cross sectional view of 25 a modification of the form of pessary illustrated in Figure 4 wherein the elongated part thereof is provided with the longitudinally extending flutes 18 which permit of the more ready reduction of the circumference of the body. The figure illustrates the full size of the pessary in cross section, the overall diameter of this fluted portion being equal to or greater than the diameter of the head.

30 While only four forms of pessary have been illustrated and described it is to be understood that the present invention is not to be limited to such forms but the illustrations have merely been made for the purpose of setting forth the principal concept of the invention which is the provision of a soluble pessary which is chambered and which contains a medicating substance.

It is believed, however, that the particular forms herein set forth are novel with applicant 45 and claims have, therefore, been directed to these forms of pessary in which medicine containing chambers are formed.

While as described the invention is directed to a chambered pessary it is to be understood 50 that the idea disclosed may be incorporated in other soluble bodies which are designed for insertion into the body cavities such, for example, as suppositories, nasal and other bougies and like bodies.

55 In forming the present pessaries in the manner illustrated it will be apparent that when the same has been placed in position the cup-like cavity on one side thereof will receive the tip of the organ which is to be treated and will act in the usual manner as a supporting means therefor and also for the surrounding organ. The form shown in Figure 4 is such that it will maintain its position while being inserted and until 60 the cavity-like forward end 15 has been properly located. The elongated design of the body serves to prevent its turning from position after insertion.

In addition to the foregoing it is to be understood that in addition to providing the pessary with chambers or a chamber in which medicinal substances may be placed for release when the body dissolves, the body itself may be medicated or simply formed of a sterile substance of suitable character as desired. It is also to be understood that the pessary may be used without having the chambers thereof filled with medicinal substance, where the supporting effect only 10 of the device is desired. In this manner the device may be made in the required size without introducing into the orifice of the body an unnecessarily large amount of material which would have to be absorbed or otherwise disposed of. 15

Other methods may be employed for adding medicinal substances to the body of the pessary in addition to filling the chambers and incorporating the medicinal agent in the material of which the pessary is formed, as, for example, 20 the body of the pessary may be perforated, grooved or slit and such areas filled with medicine and closed by a thin covering of the material of which the body is formed. Such a method may be employed in association with solid pessary 25 bodies as well as chambered ones of the character here illustrated. By this method the medicinal substance such as salve or the like would be liberated more quickly than from the chambers where a thicker wall is formed to dissolve 30 away, or if desired, the device may consist of a plurality of cells, but instead of being regularly constructed, the cells may be formed by air trapped into the substance before it hardens, so that it will have a sponge-like construction 35 and texture.

Having thus described the invention, what is claimed is:—

1. A pessary adapted to be positioned within one body organ to sterilize the same and to prevent foreign matter within said organ from entering into another body organ, said pessary consisting of a one-piece body member of soluble material, said body member having oppositely convexed side walls and oppositely concaved end 45 walls merging with said side walls, said end walls extending towards each other interiorly of the body member to provide at each end of the body member a concaved recess disposed substantially wholly within the top and bottom planes 50 of the body member, said body member containing a medicament and freeing the same in said first named organ as the body member dissolves, one of said concaved end walls being adapted to close the entrance to said second named body 55 organ and the other concaved end wall being adapted to entrap and retain foreign matter entering said first named organ until said body member is dissolved.

2. The pessary of claim 1, in which the side 60 walls are extended at one end of the body member beyond the adjacent end wall thereof to provide with such end wall an elongated open-bottom, closed-top sleeve.

RUTH W. MUNRO.
